(57) **CLAIM**

We claim the ornamental design for a measuring spoon set, as shown and described.

DESCRIPTION

FIG. 1 is a perspective view of a measuring spoon set according to the new design;

FIG. 2 is a side view of the measuring spoon set shown in FIG. 1, the opposed side view being a mirror image thereof;

FIG. 3 is a left end view of the measuring spoon set shown in FIG. 1;

FIG. 4 is a right end view of the measuring spoon set shown in FIG. 1;

FIG. 5 is a top view of the measuring spoon set shown in FIG. 1;

FIG. 6 is a bottom view of the measuring spoon set shown in FIG. 1;

FIG. 7 is an exploded side view of the measuring spoons set shown in FIG. 1;

FIG. 8 is a perspective view of a measuring spoon from the measuring spoon set according to the new design;

FIG. 9 is a left end view of the measuring spoon shown in FIG. 8;

FIG. 10 is a right end view of the measuring spoon shown in FIG. 8;

FIG. 11 is a bottom view of the measuring spoon shown in FIG. 8;

FIG. 12 is a top view of the measuring spoon shown in FIG. 8; and,

FIG. 13 is a side view of the measuring spoon set shown in FIG. 8, the opposed side view being a mirror image thereof. One measuring spoon is shown separately from the set in FIGS. 8-13 for clarity of illustration.
